Des. 183,536

Patented Sept. 16, 1958

183,536

SWIMMING POOL LADDER

Merle E. Oberholtz, Bennington, Nebr., assignor to Refinite Corporation, Ralston, Nebr.

Application March 4, 1957, Serial No. 45,068

Term of patent 14 years

(Cl. D15—8)

Fig. 1 is a side elevational view of a swimming pool ladder showing my new design.

Fig. 2 is a frontal perspective view thereof as seen in Figure 1.

I claim:

The ornamental design for a swimming pool ladder, as shown.
